UNITED STATES PATENT OFFICE.

FREDERICK H. CLUM, OF DETROIT, MICHIGAN, ASSIGNOR OF ONE-HALF TO JOSEPH W. DONALDSON, OF DETROIT, MICHIGAN.

TOOTHBRUSH AND PASTE HOLDER.

Application filed November 8, 1920. Serial No. 422,447.

To all whom it may concern:

Be it known that I, FREDERICK H. CLUM, a citizen of the United States of America, residing at Detroit, in the county of Wayne and State of Michigan, have invented certain new and useful Improvements in Toothbrushes and Paste Holders, of which the following is a specification, reference being had therein to the accompanying drawings.

10 This invention relates to a combined tooth brush and paste holder or a tooth brush which is arranged to hold the paste and deliver it, as desired, to the brush, and its object is to provide a compact construction of 15 neat appearance wherein the refilling of the device is greatly facilitated and a positive and accurate feeding of the paste to the brush secured without waste of material.

A further object is to provide a tooth brush of this character which is sanitary and in which the air is excluded from the tooth paste carried thereby at all times except when the brush is being used and in which the construction facilitates the cleaning of 25 the device and permits of the detachment and replacement of the brush proper.

A further object of the invention is to provide certain other new and useful features, all as will hereinafter more fully appear.

With the above and other ends in view, the invention consists in providing a handle construction to receive a paste container and to provide a paste container with means 35 forming a closure therefor for forcing the paste from the container. The invention further consists in certain other matters hereinafter set forth and more particularly pointed out in the appended claims, reference being had to the accompanying drawings, in which.

Figure 1 is a longitudinal section through a device, illustrative of the invention;

Fig. 2 is a plan view of a portion of the 45 same;

Fig. 3 a detail showing an elevation of an end portion of the tubular handle;

Fig. 4 is a sectional detail of a cap for the end of the tubular handle;

Fig. 5 is an end elevation of Fig. 4;

Fig. 6 is a transverse section substantially upon the line VI—VI of Fig. 1;

Fig. 7 is an elevation of a paste holder or tube detached and showing portions there-

of in section and broken away to more 55 clearly disclose the construction; and

Fig. 8 is a side elevation of the device as shown in Fig. 1, with the enclosing cap or brush shield in place.

As illustrative of an embodiment of the 60 invention, the device as shown in the drawings comprises a brush block 1 which is provided with the usual tufts of bristles 2 secured in the block in any suitable manner. To hold this block, a brush back 3 is provided having a shank portion 4 extending 65 from one end thereof which shank terminates in a screw-threaded nipple 5 to receive a tube or hollow handle 6 which is internally screw-threaded at one end to engage 70 the nipple. The shank 4 of the brush holder or back is formed with a ledge 7 adjacent the shank portion 4 to engage one end of the brush block 1, and this shoulder is provided with an opening or short bore extending 75 longitudinally of the shank to receive a pin 8 which is preferably integral with the brush block 1. Adjacent the opposite or free end of the brush block, said block is provided with a hole extending there-through to receive a discharge nipple 9 which is inserted into this hole between the tufts of bristles and is provided with a screw-threaded inner end to engage a screw-threaded opening in the brush back or 85 holder 3, which holder is provided with a longitudinal channel 10 communicating at one end with the hollow nipple 9 and is extended through the shank portion 4 with its rear end opening into an internally screw-threaded socket 11 formed axially of the nipple 5 and arranged to receive the screw-threaded neck portion 12 of a paste tube or 90 container 13 which is of a size to fit within the tubular casing or handle 6.

When the paste tube is inserted in the handle 6 and screw-threaded into engagement with the socket 11, paste may be forced therefrom by means hereinafter described, and this paste will pass through the channel 100 10 in the brush holder into the nipple 9 and thence out through the nipple and through a flexible extension 14 of the nipple, said extension being preferably a thin rubber tube which is slipped over the end of the nipple 105 and extends to near the ends of the bristles to deliver the paste to that portion of the bristles which come in contact with the teeth

when the brush is used. The extension 14 being of thin rubber will not interfere with the free bending of the bristles and its presence will not be apparent to the user of the brush while he is using it in brushing his teeth.

By means of the described construction, the brush block or member which carries the bristles may be readily detached from the holder or back by simply inserting a suitable instrument, indicated at 15, in dotted lines, into the end of the nipple 9 for turning the nipple to unscrew it from engagement with the holder. The removal of this nipple permits the brush block to be moved endwise to disengage the stud or pin 8 from the opening into the holder, and therefore, when the bristles become worn this brush block may be readily detached and a new block with new bristles slipped into place. The block and nipple may also be readily detached for the purpose of cleaning out the channel through which the paste is delivered.

For convenience in handling, the tooth paste is put up in tubes by the manufacturer in the usual manner, the body and nipple end of these tubes being of the usual construction, and when put up for shipment, the nipple being closed in the usual manner by a cap 16 (as shown in Fig. 7). Instead of the tube being closed at its opposite end by folding it into a seam as is the usual practice, this end of the tube is closed by a suitable disk or piston 17 which fits closely within the tube and has a cylindrical wall 18 of sufficient length to guide the piston in its movement in the tube. The wall of the tube, at its extreme end, is crimped or turned inwardly, as at 19, to engage the cylindrical wall of the piston and when the tube is filled with paste by the manufacturer, the piston is placed in the open end of the tube and then the wall of the tube crimped over to hold the piston in place. This piston, therefore, forms a closure for the end of the tube and every tube, when put out by the manufacturer is provided with this end closure.

A screw-threaded rod 20 extends through an axial screw-threaded opening in the piston 16 and through the paste contained in the tube to the opposite end thereof. This rod or stem has a formed head 21 on its outer end by means of which the rod is turned and when the tube is put upon the market by the manufacturer of the paste, it will contain the rod and piston with the head 21 of the rod lying within the chamber formed in the end of the tube by the cylindrical wall 18 of the piston. Therefore when the paste tube is placed upon the market, the piston and the screw-threaded rod for moving the piston along the tube and forcing the paste therefrom, are in operative position with the head 21 which is provided for turning the rod, in a position to be engaged by a

socket 22 upon a cap 23 adapted to be applied to the end of the cylindrical casing or handle 6. This cap 23 is detachably held upon the end of the casing by providing an internal screw-thread 24 on an intermediate portion of the cap and forming a reduced end portion 25 of the casing 6 with a screw-thread 26 to engage the screw-threaded portion 24 of the cap. By slipping the cap over the end of the casing, the screw-threads 24 and 26 are brought into engagement and then by a turning movement the cap is screwed on to the end of the casing until the screw-threaded portion 24 passes out of engagement with the screw-threads 26 and lies within the reduced end portion 25 of the casing. The cap will then turn freely upon the end of the casing without moving endwise and may therefore be turned to operate the rod 20, the head 21 of which is engaged with the socket 22 on the cap when the cap is placed upon the end of the casing. With the paste tube in place within the casing and the cap 23 upon the end of the casing with its socket 22 engaged with the end 21 of the screw stem 20, said cap may be turned to turn the stem 20 and by such turning movement force the piston or plunger 17 endwise of the paste tube and force the paste therefrom out through the channel 10 and nipple 9 to the brush. A very accurate feeding of the paste is secured by this arrangement as none of the contents of the paste tube can escape except through the discharge channel and nipple and the piston provides a positive means for forcing every particle of paste from the tube. There is, therefore, no waste of dental paste either by reason of any residue remaining in the tube or by reason of more paste being discharged than is necessary. The construction also provides a very sanitary arrangement in that all parts are enclosed against dirt or dust getting into the channel or into the container for the tube and a new supply of paste may be quickly provided by simply unscrewing the casing 6 and removing the tube from which the paste has been used and screwing a new paste tube into engagement with the shank of the brush holder, the means for forcing the paste from the tube being in operative position within the new tube so that by slipping the casing over the tube and engaging the cap therewith the device is again ready for use.

To protect the bristles of the brush from injury and dirt and also to provide a tight closure for the brush so that the dental paste in the end of the discharge nipple 9 will not harden therein and block up the passage, a tubular shield 27 is provided which is formed with a tubular end portion 28 to fit closely over the end of the shank 4 and adjacent end of the casing 6, and this shield may be flattened or otherwise broadened out

to fit over and properly inclose the brush with its bristles.

Obviously, changes in the form, arrangement and combination of parts as shown in the drawing may be made within the scope of the appended claims, without departing from the spirit of the invention, and I do not therefore limit myself to the particular construction shown.

Having thus fully described my invention, what I claim is:—

1. In a device of the character described, the combination of a brush block, a holder having a seat to receive the brush block and formed with a longitudinal channel opening through said seat at one end, means for forcing dental paste into the opposite end of said channel, and means for detachably holding said brush block seated upon its seat.

2. A device as characterized in claim 1, and including a discharge nipple communicating with the channel in the holder and engaging the holder and block to detachably hold the block in place upon the holder.

3. A device as characterized in claim 1, and wherein the brush block is provided with tufts of bristles and detachably seated upon the seat provided therefor on the holder and including a screw-threaded nipple extending through the brush block between the bristle tufts and engaging an opening in the holder, said nipple being in communication with the longitudinal channel in the holder, and a flexible tubing on the nipple forming a continuation thereof to conduct the dental paste to the outer ends of the bristles.

4. In a device of the character described, the combination of a holder, a brush holder having a longitudinal channel, a brush block carried by the holder and provided with tufts of bristles, said holder being also formed with a screw-threaded socket in communication with said channel, a paste tube having a nipple to engage the screw-threaded socket, a casing enclosing the paste tube and connected to the holder, and means for forcing the paste from the tube.

5. In a device of the character described, the combination with a brush holder having a shank portion and formed to provide a

seat and a shoulder adjacent an end of said seat and shank, said holder being also formed with a longitudinal channel extending through said shank and opening through said seat, a brush block carrying tufts of bristles and formed to seat upon said seat against said shoulder, said block being also formed with an opening opposite the end of said channel, means on said block for engaging said shoulder and detachably holding one end of said block upon its seat, a tubular member in the opening in the brush block and forming a continuation of said channel, said member being detachably engaged with said holder to hold the block in place upon its seat, a tubular casing engaging the free end of said shank at one end, a paste tube within said casing to discharge paste into the channel of the brush holder, and means within the tube for forcing the contents therefrom.

6. A device of the character described, comprising a brush holder formed with a seat for a brush block, and with a shank portion at one end, said holder being provided with a channel opening at one end through said seat and at its opposite end through said shank, said shank being also formed with a screw-threaded socket into which the channel opens, a brush block having bristle tufts seated upon said seat and provided with an opening through the block between the tufts, a nipple extending through the opening in the block and having screw-threaded engagement with the holder to hold the block in place, said nipple being in communication with the channel in the holder, a paste tube having a screw-threaded nipple in engagement with the screw-threaded socket in the holder, a tubular casing sleeved over the tube and detachably engaged at one end with the holder, and means for forcing paste from the paste tube through its nipple into the end of the channel leading from said screwthreaded socket.

In testimony whereof I affix my signature in presence of two witnesses.
